DISPENSING FAUCET FOR CANNED BEVERAGES

Peter Zelisko, Chicago, Ill., assignor to Atlantic Brewing Company, Chicago, Ill., a corporation of Illinois

Filed Aug. 11, 1964, Ser. No. 81,246

Term of patent 7 years

(Cl. D2—3)

FIG. 1 is a top plan view of a dispensing faucet for canned beverages showing my new design;

FIG. 2 is a side elevational view thereof;

FIG. 3 is a rear elevational view thereof as seen from the right hand side of FIG. 2;

FIG. 4 is a bottom plan view thereof;

FIG. 5 is a side elevational view showing the side opposite to that shown in FIG. 2; and

FIG. 6 is a front elevational view as seen from the right hand side of FIG. 5.

I claim:

The ornamental design for a dispensing faucet for canned beverages, substantially as shown.
